UNITED STATES PATENT OFFICE

135,045

DESIGN FOR A ROOFING SHINGLE

Oscar A. Bigler, Chicago, Ill., and Millard S. Larrison, Frankford, Pa., assignors to United States Gypsum Company, Chicago, Ill., a corporation of Illinois

Application May 22, 1942, Serial No. 106,977

Term of patent 14 years

To all whom it may concern:

Be it known that we, Oscar A. Bigler and Millard S. Larrison, citizens of the United States, residing, respectively, at Chicago, in the county of Cook and State of Illinois, and Frankford, in the county of Philadelphia and State of Pennsylvania, have invented, a new, original, and ornamental Design for a Roofing Shingle, of which the following is a specification, reference being had to the accompanying drawing, forming a part thereof.

The figure is a plan view of a roofing shingle embodying the design.

We claim:

The ornamental design for a roofing shingle, substantially as shown.

OSCAR A. BIGLER.
MILLARD S. LARRISON.
